A. MEYER ET AL

METHOD OF AND APPARATUS FOR TREATING TIMBERS AND THE LIKE

Filed May 8, 1922

Patented May 27, 1924.

1,495,863

UNITED STATES PATENT OFFICE.

AUGUST MEYER, OF MINNEAPOLIS, MINNESOTA, AND PHILIP R. WALSH, OF ST. LOUIS, MISSOURI.

METHOD OF AND APPARATUS FOR TREATING TIMBERS AND THE LIKE.

Application filed May 8, 1922. Serial No. 559,268.

To all whom it may concern:

Be it known that we, AUGUST MEYER and PHILIP R. WALSH, citizens of the United States, and residents of the city of Minneapolis, county of Hennepin, and State of Minnesota, and the city of St. Louis and State of Missouri, respectively, have invented certain new and useful Improvements in Methods of and Apparatus for Treating 5 Timbers and the like, of which the following is a specification containing a full, clear, and exact description, reference being had to the accompanying drawings, forming a part hereof.

10 Our invention relates to improvements in the method of and apparatus for treating timbers, and the like, and has for its primary object a method of and apparatus for treating a predetermined portion of 15 the lower or butt ends of telephone poles, pilings, posts and similar timbers.

A further object is a method of treating timbers and the like with a preservative whereby a deeper penetration of the preservative in the wood cells, ducts or vessels 20 is possible and at the same time not losing any of the more volatile essential oils.

This is an improvement on Letters Patent 25 No. 1,422,119 issued to us on the 11th day 30 of July, 1922.

The drawing illustrates the device by which our method is carried out.

In the construction of our invention we 35 employ a treating tank 1. This tank is preferably vertical, and is located in a pit. Located adjacent the edge of the pit is a storage tank 2, which is connected to the bottom of the treating tank by means of a pipe 3. This pipe 3 has located therein 40 a valve 4 for controlling the flow of liquid from the storage tank to the treating tank. The pipe 3 is provided with an upwardly extending portion 5, which leads into the top of the tank. The portion 5 is also provided with a valve 6 whereby it can be 45 closed off.

Immediately below the valve 6 is a T 7, which is provided with a valve 8. This valve can be used for various purposes, 50 such as draining the tank or cleaning out the pipes or tank.

The tank 1 is provided with a cover 9, which is secured to the flange 10 of the tank by means of bolts 11 so as to make 55 an air and liquid tight connection. The

tank 1 is also provided with a perforated false bottom 12, which is raised slightly above the bottom of the tank 1 and beneath this false bottom is placed a heating coil 13. The tank 2 is likewise provided with 60 a heating coil 14. These heating coils are connected to a steam line 15 by means of branch pipes 16, which branch pipes are provided with valves 17 so that the flow of steam into the coils can be controlled. 65 The steam pipe 15 terminates in a boiler 18.

Located adjacent the pit is an air compressor 19, a vacuum pump 20 and a liquid pump 21. These pumps are operated by means of branch pipes 22, 23 and 24, which 70 are connected to the steam pipe 15. These branch pipes are provided with valves 25 for controlling the admission of steam to the various pumps.

The branch pipe 24 is also provided with 75 a valve 26, the purpose of which will be explained later. Connected to the air pump 19 is a pipe 27, which enters the treating tank 1 near its top. This pipe is provided with a valve 28. The vacuum pump 20 is 80 provided with a pipe 29, which enters the tank 1 at a short distance below the pipe 27. The pipe 29 is also provided with a branch 85 30 which enters the tank 1 at a point near its bottom. The pipe 29 is provided with a valve 31, this valve being interposed in the pipe between the branch 30 and the pump 20.

Located in the pit and adjacent the tank 1 is a chamber 32. This chamber is connected at its bottom to the lower portion 90 of the tank 1 by a pipe connection 33. A second pipe 34 connects the upper portion of the chamber 32 with the upper portion 95 of the tank 1. Within the tank 32 is a float 35 which is provided with a stem 36, this stem extending through the top 37 of the float chamber. The top 37 is provided with a packing gland 38 so as to prevent the leakage of air around the stem 36. The upper portion of the stem 36 is provided 100 with a plurality of openings 39, into which a pin 40 is adapted to fit. This pin 40 extends through the slotted end 41 of the lever 42. This lever is pivotally mounted 105 at the point indicated by the numeral 43 to a stand 44. The opposite end of the lever 42 is provided with a link 45 which is connected to the handle 46 of the valve 26. The lever 42 is also provided with a 110

weight 47. This weight is secured between the pivot 43 and the slotted end 41.

In order to prevent the timbers from raising in the tank 1 when liquid is admitted, we make use of a false top 48. This top is perforated so that air can pass freely therethrough.

The operation of our device is as follows:

The timbers to be treated are first placed 10 in the treating tank 1, after which the false top 48 is placed in position. The cover 9 is then secured in place, and the vacuum pump 20 placed in operation. This exhausts the air within the tank and also 15 draws out air from the wood cells and ducts so as to create a partial vacuum within the timbers. Before this time, if found desirable, steam may be admitted to the coil 13 through the pipe 16 or directly to the timbers which will assist in driving off moisture from the timbers, or in other words, 20 seasoning them.

After the vacuum has been maintained 25 for a sufficient length of time, the valve 31 is closed. The float 35 is regulated by means of the openings 39 and pin 40 and the valve 4 then opened. The vacuum in the chamber 1 now causes the preserving fluid in the tank 2 to be drawn violently 30 downward into the tank 1, where it rises. This liquid also rises in the chamber 32, and when a predetermined height has been reached the lever 42 will be in substantially 35 a horizontal position, as indicated in the drawing. The valve 4 is then closed, the air pump 19 started, and the valve 28 opened.

Compressed air is now admitted into the 40 treating tank above the liquid. This compressed air imparts pressure to the liquid and forces it into the timbers. The compressed air also flows into the chamber 32 through the pipe 34, so that the level of liquid in the chamber 32 will remain the same as in the treating tank 1. At this 45 time the valve 26 is closed off by means of the float 35 and rod 36 acting upon the lever. The steam valve 25 leading to the pump 21 is opened, as are the valves 48 and 49, which are mounted in the supply line 50 and suction line 51 respectively, the supply line 50 leading into the tank 1 near its bottom and the suction line 51 into the tank 2.

55 When the valves 48 and 49 have been opened and any absorption by the timbers takes place, the float 35 will be lowered. This lowering of the float will cause the lever 42 to be rocked and open the valve 26 which places the pump 21 in action and pumps additional liquid into the treating chamber until the original level is again reached, when the valve 26 is closed and the pump stopped.

60 The pressure within the tank 1 is main-

tained until the timbers have been sufficiently treated. Then the valve 6 is opened and the compressed air within the treating chamber 1 will force the liquid therefrom through the pipes 3 and 5 and into the storage chamber. After the surplus treating liquid has been forced from the treating chamber into the storage chamber, a second vacuum is applied to the treating tank in order to extract any excessive 70 amount of preservative absorbed by the timber. This has been found preferable, because there is always a certain amount of excessive preservative retained by the timber, which is not necessary for its preservation, and which gradually seeps out and is lost, thus causing a waste of preservative. After the second vacuum has been applied for a sufficient length of time the air is admitted to the treating chamber, the top or cover removed, after which access can be had to the timbers for their removal from the tank.

By the use of our device it is possible to automatically maintain a constant level of 90 the liquid within the treating chamber so that the liquid will penetrate deeply into the wood to the desired height on the timber, while were this liquid level not maintained, the absorption of the preservative by the timbers would cause a gradual lowering and consequently it would be necessary to treat a greater length of timber than was actually required.

Having fully described our invention, 100 what we claim is:

1. The herein described process of treating 105 a predetermined portion of a piece of timber with a preservative liquid by immersing the terminal portion thereof to the desired extent in the treating liquid, producing a pressure above the liquid and about the free extending portion of the timber to cause a penetration of the liquid and maintaining a constant liquid level about the timber being treated.

2. The herein described method of treating 110 at one and the same time, predetermined portions of timbers with a preserving liquid, which consists in assembling a plurality of such timbers in a substantially upright position and immersing the terminal portions thereof to the desired extent in the treating liquid and producing a pressure above and acting on the surface of the liquid and about the free extending portions of the timbers to cause a deep penetration of the liquid into the immersed portions of the bodies of the timbers and maintaining a constant level of the liquid around the timbers.

3. The herein described method of treating 115 a timber with a preserving liquid, which consists in placing it within an air and liquid tight tank, creating a vacuum in the 120

- tank to withdraw air and moisture from the cells of the timber, thereafter admitting a sufficient quantity of the treating liquid to immerse a terminal portion of the timber to the desired point producing a pressure above the liquid and about the free extending portion of the timber to cause a deep penetration of the liquid into the immersed portion of the body of the timber, and maintaining a constant liquid level within the tank.
4. An apparatus for the simultaneous treatment of predetermined portions of a number of timber poles, piling and the like, comprising a treating tank arranged in a substantially upright position and provided with a closure means and uninterrupted from top to bottom to permit the introduction of a number of timbers into the tank which are supported at their lower ends, a liquid connection leading to the tank near its bottom through which is delivered a preservative liquid, an air pressure line connection with the tank at the upper portion thereof, a vacuum line connection with the tank, and means whereby a constant liquid level may be automatically maintained within the tank.
5. An apparatus for the simultaneous treatment of predetermined portions of a number of timber poles, piling and the like, comprising a treating tank arranged in a substantially upright position and provided with a closure means and uninterrupted from top to bottom to permit the introduction of a number of timbers into the tank which are supported at their lower ends, a liquid storage tank, a liquid connection leading from the storage tank to the treating tank at a point near its bottom through which is delivered a preservative liquid, an air pressure line connected with the tank at the upper portion thereof, a vacuum line connection with the tank, means whereby a
- constant liquid level may be automatically maintained within the tank, and means for supplying heat to the interior of the storage and treating tanks.
6. The herein described method of treating a timber with a preserving liquid, which consists in placing it within an air and liquid tight tank, creating a vacuum in the tank to withdraw air and moisture from the cells of the timber, thereafter admitting a sufficient quantity of the treating liquid to immerse a terminal portion of the timber to the desired point producing a pressure above the liquid and about the free extending portion of the timber to cause a deep penetration of the liquid into the immersed portion of the body of the timber, maintaining a constant liquid level within the tank, and supplying heat to the treating liquid both before and after its delivery into the tank.
7. The herein described method of treating a timber with a preservative liquid, which consists in placing it within an air and liquid tight tank, creating a vacuum in the tank to withdraw air and moisture from the cells of the timber, thereafter admitting a sufficient quantity of treating liquid to immerse a terminal portion of the timber to the desired point producing a pressure above the liquid and about the free extending portion of the timber to cause a deep penetration of the liquid into the immersed portion of the body of the timber, maintaining a constant level of treating liquid within the tank during the pressure period, withdrawing the treating liquid from the tank, and then creating a vacuum within the tank to withdraw the excess treating liquid contained within the cells of the timber.
- In testimony whereof, we have signed our names to this specification.

AUGUST MEYER.
PHILIP R. WALSH.
